UNITED STATES PATENT OFFICE.

BURT EDWIN STORR, OF WILLITS, CALIFORNIA.

DOOR AND WINDOW SECURER.

No. 837,595.

Specification of Letters Patent.

Patented Dec. 4, 1906.

Application filed April 27, 1906. Serial No. 313,992.

To all whom it may concern:

Be it known that I, BURT EDWIN STORR, a citizen of the United States, residing at Willits, in the county of Mendocino and State of California, have invented new and useful Improvements in Door and Window Securers, of which the following is a specification.

This invention is a door and window securer, and more particularly a portable device of this kind comprising a brace which is jammed between a door and the floor or between two sliding window-sashes, whereby the door or window will be securely held closed.

The object of the invention is to provide a simple and efficient securing device which can be readily applied and which when not in use can be folded in a small and compact form for convenience in carrying it.

In the accompanying drawings, Figure 1 is a side elevation of the invention in position for securing a door. Fig. 2 is a top plan view. Fig. 3 is a bottom plan view. Fig. 4 is a bottom plan view showing certain parts in another position. Fig. 5 is an edge view showing the device folded.

Referring specifically to the drawings, 7 and 8, respectively, denote two arms or members of substantially equal length which are connected by a hinge or other joint. The outer ends of the arms are formed with sharp points or teeth 9.

At 10 is indicated a sliding sleeve mounted on the arm 8 and secured thereto by a pin 11, extending through a slot 12 in said arm. This sleeve is adapted to be extended over the joint between the arms when they are straightened out to lock them in this position. The sleeve extends around one edge of the arms only, and on one side it is cut away, as at 13, to form a recess which receives the hinge-knuckles 14 when the sleeve is in locking position, as shown in Fig. 3. The pin 11

also serves as a pivot on which the sleeve may be swung outwardly sufficiently to clear 45 the hinge-knuckles, as shown by dotted lines in Fig. 4.

To apply the invention, one end is placed on the floor and the other end against the door. The arms 7 and 8 are then straightened out by pressing down on the joint, which forces the teeth 9 into the floor and door. The sleeve 10 is then swung outwardly from the arm 8, as shown by dotted lines in Fig. 4, and slid forwardly and pushed down, so as to extend over the joint, as shown in Figs. 1, 2, and 3, the hinge-knuckles extending into the recess 13. For securing a window the device will be placed between the top of the lower sash and against the inner side of the upper sash. When not in use, the sleeve is slid back on the arm 8 and the arms are then folded, as shown in Fig. 5. In this position it can be conveniently carried in the pocket.

I claim—

1. A door and window securer comprising a pair of arms connected by a hinge, and a sliding and laterally swinging sleeve mounted on one of the members and extensible over the joint.

2. A door and window securer, comprising a pair of arms connected by a hinge, one of said members being slotted, and a sleeve slidably mounted on the slotted member, 75 and having a pin extending through the slot, said sleeve being extensible over the joint, and having a recess on one side to receive the hinge-knuckles.

In testimony whereof I have signed my name to this specification in the presence of two subscribing witnesses.

BURT EDWIN STORR.
